UNITED STATES PATENT OFFICE

WILLIAM O. YANCEY, OF CHICAGO, ILLINOIS

CHILD'S TOY VEHICLE

Application filed July 1, 1929. Serial No. 375,216.

This invention relates to improvements in child's toy vehicle, and more particularly to a self propelled vehicle in which the forward portion is a walking automaton or figure 5 which keeps pace with the forward movement of the vehicle.

The object of the invention is to provide a novel and practical toy for children including a walking figure having legs which support 10 the forward end of the vehicle and manipulated to function as though drawing the vehicle and its passenger.

The novel features of the vehicle are disclosed in the preferred embodiment of the 15 invention illustrated in the accompanying drawing, in which

Figure 1 is a perspective view of the vehicle.

Figure 2 is a view in rear elevation of the 20 rear driving wheels and the seat of the vehicle.

Figure 3 is a view in vertical section through the walking figure; and

Figure 4 is a perspective view of the lower 25 portion of the body showing the action of one of the legs.

As clearly shown in Figure 1, the vehicle resembles generally a child's velocipede or 30 pedal-propelled tricycle in which the forward steering wheel has been replaced by an upright walking figure 1, such as a large animated doll, facing in a forward direction. Immediately behind the figure is a two-wheeled vehicle having a frame of the usual 35 solid or tubular bar construction. As shown in Figure 2, the rear end portion of the frame consists of an upright inverted U-shaped frame member 2a having bearings at each end which support a transverse shaft 3 to the 40 ends of which the two wheels 4, 4 are fixed. The crank shaft has a pair of oppositely offset cranks 3a, 3a, at its central portion, carrying a pair of connecting rods 5, 5 extending forwardly and pivotally connected with a 45 pair of treadle bars 6, 6.

Integral with the rear frame member 2a is a forwardly extending yoke or Y-shaped frame member 2b having an eye at its forward end which engages an eye bolt 7 anchored in the back of the figure, 1, just

below the waist line and forming a swivel connection therewith. Midway of the ends of the Y-shaped frame member 2b is a depending arm 2c having a bifurcated end which support the treadle bars 6, 6 adjacent their rear or connecting rod ends. The treadle bars assume an inclined position in an upward direction from rear to front, and at their forward and upper ends are pedal-like foot rests 6a, 6a.

Supported on the vehicle frame is a flat seat 8 extending rearwardly beyond the frame so that the child sits over the wheels with the weight well to rear. The seat is extended at the front in the form of a narrow neck or bar 8a which is connected to the figure 1 independently of the vehicle frame, and at a point just above the eye bolt 7.

The seat 8 is not fast to the vehicle frame, but is designed to be supported thereon so that it can rock slightly from side to side, and therefore is pivotally mounted on the frame by means of a bracket 9 fixed to the under side of the seat near its central portion, and having pivotal connection with the rear 75 frame member 2a, as at 10 (Figure 2).

The forward end of the narrow extension 8a of the seat is connected with the body of the figure 1 by means of a ring or band 11 having a rearwardly opening socket member 12 fixed thereto and into which said end portion of the seat is inserted. The ring 11 fits somewhat loosely in a groove about the waist portion of the body 1, so that the latter is free to turn through a small angle in opposite directions, the angle of turning being limited by a lug 12b on the ring engaging a slot 13 in the body, the length of the slot being such as to limit the turning of the figure within a rather small arc, and for the reason that the figure 1 cannot be maneuvered at will, but must proceed in a general straight line and hence the steering is confined to keeping the vehicle in a generally straight course.

The body of the figure may be of any suitable construction, which will afford lightness and durability. A hollow sheet metal body would be desirable, but for convenience of illustration, it may be assumed that the body is of a solid material such as wood, and of a

generally cylindrical shape, but conforming somewhat to the contour of the human body. The arms 14, 14 are pivotally attached to the body so that they can swing at the sides, and are used for guiding the figure in a straight path when swung backwardly and held in the hands of the child seated behind.

The body is supported on legs 15, 15 which are mounted on opposite sides of the body 10 near its lower end, and are shown as straight members of equal length, but without joints at knee or ankle. Feet 16, 16 are provided at the lower extremities of the legs, the same being plate-like supports having rounded 15 or curved bottom surfaces. Thus, as shown in Figure 1, the feet extend substantially the same distance forwardly and rearwardly of the legs and are rounded on their bottoms in a horizontal direction. Moreover, they are 20 rounded transversely on their bottoms as through an arc described from a point somewhere near the center of the body. As will presently be seen, it is this particular curvature of the bottoms of the feet which permits 25 the figure to walk.

The upper ends of the legs lie in laterally facing recesses 17, 17 cut into the body on opposite sides and are pivotally connected to the body by a rod 18 extending through the 30 body from side to side, the ends of the rods forming bearings for the legs at points a short distance below their upper ends, so that each leg has a short arm above its pivot which swings back and forth in the enlarged 35 or widened upper portion of its recess. Acting on the upper end of each leg is a coil spring 19 lying in a horizontal position between the front edge of the leg and the forward face of the recess, and so located is normally under compression and assists in swinging 40 the lower portion of the leg forwardly with each step. Also connected with the upper end of each leg is a rod 20 connecting the same with the upper end of the treadle bar 6 on the same side. Each of these rods has a 45 slotted forward end portion 20a engaging a pin 21 anchored in the leg above its pivot. The rear ends of the rods 20, 20 are bent to form eyes 20b which pass through similar 50 eyes 6b at the ends of the treadle bars 6, 6. To conceal the leg recesses in the body a circular band 22 of thin metal surrounds the body and is provided with openings 22a through which the rods 20—20 pass.

55 The vehicle as thus constructed is propelled in the following manner: The child sits on the seat over the wheels and straddles the narrow forward extension thereof, with his feet on the treadle bars, which are alternately depressed to transmit power to the wheels through the connecting rods 5, 5 and cranks 3a, 3a in the usual manner. The method of propelling the vehicle therefore is not essentially different from the ordinary tri- 60 cycle.

But the figure, 1, must take steps to keep pace with the forward motion of the vehicle, and this is accomplished in the following manner: As the child applies pressure alternately on the treadle bars, the weight of his body naturally shifts from one side to the other, the weight being greater on the side on which the pressure is being exerted. Since the seat 8 is pivotally mounted on the vehicle frame, it not only rocks from side to side but 70 causes the figure, 1, to rock or tilt with it, this being due to the fact that while the vehicle frame is loosely connected with the figure, the seat is fixed thereto so far as any relative tilting movement is concerned. Thus 75 assuming in Figure 1 that the treadle bar on the near side is depressed, the weight thrown toward the same side causes the seat to tilt in the same direction as well as the toy figure, 1, which can rock in either direction on its 80 rounded feet. Now as the leg on the near side, which is extended forwardly, comes in contact with the ground, the leg on the far side is released as its foot leaves the ground and is swung forward by the action of its 85 spring 19 for the next step. In the meantime the vehicle is moving forward so that the figure rocks forward on the rounded foot of the near leg until the rocking of the seat in the opposite direction as the far pedal is depressed, tilts the figure onto the extended far leg and releases the near leg. Thus the figure "walks" ahead with a stiff-legged swaying gait in unison with the treadle action propelling the vehicle from behind.

90 It will be observed that while the treadles 6, 6 are connected with legs of the toy figure, the connection is such that no power of locomotion is imparted to the legs inasmuch as during the downward power stroke of a treadle the slotted end of the rod 20 merely slides forward on the pin 21. However, during the upward stroke of either treadle bar, the rod 20 slides in the opposite direction until the forward end of the slot engages the pin 21 whereupon it exerts a pull at the upper end of the leg assisting the spring in swinging the same to its forwardly extended position.

95 It follows, therefore, that the walking figure simply walks ahead of the vehicle at a pace equal to the speed that the vehicle can be driven. It is necessary, therefore, to gear the vehicle quite low, so that the linear speed of the wheels is not in excess of the rate at which the figure can "walk".

100 The same mechanism may be adapted to four-legged animals, so that horses, dogs, and the like, may be used as well as two-legged figures. It will be understood, therefore, that the character represented by the walking figure may be varied without departing from the spirit of the invention.

I claim:—

1. A wheeled vehicle having a pair of legs 105

5 pivotally mounted in advance of the wheels thereof and spring actuated for walking motion along the ground as the vehicle moves in a forward direction, and means for tilting a portion of said vehicle from side to side to lift said legs alternately from the ground so that one may be extended ahead of the other.

10 2. A vehicle comprising a frame having wheels at the rear thereof, a walking figure connected to the forward end of said frame and having legs pivotally connected with said figure for swinging movement in parallel planes and provided with foot-like extremities, a seat pivotally mounted on said frame and also connected with said figure, said seat being tiltable to rock said figure from side to side as the vehicle is propelled, and springs acting on said legs to swing one 15 ahead of the other as they are alternately lifted from the ground in the rocking motion of said figure.

20 3. A toy vehicle comprising a wheeled frame, a walking figure having swivel connection with the forward end of said frame, a pair of legs pivotally mounted for walking motion along the ground as the vehicle moves in a forward direction, pedal actuated driving members for said wheels operatively connected with said legs for swinging the same in one direction, a seat pivotally mounted in said frame and connected with said figure, said seat being tiltable from side to side to rock said figure, and tension means acting 25 on each leg to swing the same ahead of the other as it is lifted from the ground with the rocking motion of said figure.

30 4. A vehicle comprising a frame, a pair of wheels at the rear of said frame, a walking figure having several connections with the forward end of said frame, and having legs in supporting contact with the ground and pivotally connected with said figure for swinging movement in parallel planes, said 35 legs having feet with longitudinally and transversely rounded bottoms, pedal operated means for propelling said vehicle, a seat pivotally mounted on said frame and connected with said figure to rock the same from side to side as the pedals are alternately depressed, and springs acting on said legs to swing one ahead of the other as they are alternately lifted from the ground by the 40 45 50 55 rocking motion of said figure.

55 Signed at Fort Worth this 26th day of June, 1929.
